UNITED STATES PATENT OFFICE.

REUBEN D. ROTH, OF GETTYSBURG, PENNSYLVANIA.

TYING IMPLEMENT.

Specification of Letters Patent. Patented Jan. 2, 1917.

1,210,845.

Application filed June 16, 1914. Serial No. 845,461.

To all whom it may concern:

Be it known that I, REUBEN D. ROTH, a citizen of the United States, residing at Gettysburg, in the county of Adams and State of Pennsylvania, have invented certain new, and useful Improvements in Tying Implements, of which the following is a specification.

This invention relates to implements for bundling corn shocks, and more particularly to that class of implements known as tying implements.

The object of my invention resides in the provision of a novel tying implement, said tying implement being provided with an improved means whereby to facilitate the manipulation of the same.

Another object of my invention is to provide a tying implement which in construction, is simple and effective, and is so formed as to permit the same to be used as a husking peg if so desired, previous to the tying operation.

With the above and other objects in view, this invention resides preferably in the construction, combination and arrangement of parts as set forth hereinafter in the annexed specification and illustrated in the accompanying drawing in which:—

Figure 1 is a perspective view of a corn husking peg constructed in accordance with the preferred form of my invention. Fig. 2 is a side elevation of the same, showing the free ends of the cord or twine, hereinbefore mentioned, secured thereto. Fig. 3 is a cross section of the husking finger or blade showing the contour of the same.

Similar reference characters indicate similar parts throughout the various views of the drawing.

Referring more particularly to the drawings in which the preferred form of my invention is illustrated, I provide a bar 1 of metal or other suitable material having one end thereof formed to provide a finger 2, the opposite end thereof being provided with a handle, which in the present instance comprises a ring 3 integrally formed with the bar 1, as is more clearly shown in Fig. 2, the ring 3 is supported from the bar 1 at a point slightly below the center of the ring, thus allowing of the comfortable engagement of the finger of the user's hand therewith, as will be more fully set forth herein-after. As shown to advantage in Fig. 3, the

finger 2 is preferably concavo-convex as shown at 2' throughout its longitudinal axis, whereby to assist the same to perform its functions.

To facilitate the manipulation of the finger 2, I provide laterally extending projections 4 and 5 upon the opposite faces of the bar 1, and intermediate the ends thereof.

As is shown to advantage in Fig. 1, one face of the projection 4 is preferably concaved as indicated at 6, this projection 4 providing a thumb engaging portion which assists in the manipulation of the device. The lateral projection 5 formed on the opposite face of the bar 1 is adapted to be received between the fingers of the user's hand, and is so positioned as to assist the projection 4 in performing its intended functions.

For the purpose of convenience in showing, the device has been shown in Figs. 1 and 2 in an opposite position relative to its upper and lower sides to which the same would be, when in use, that is, the device would be turned completely over and it has been found in use that the most convenient manner in which to manipulate the same is to insert the little finger of the right or left hand into the ring or handle 3, allowing the other three fingers of the hand to engage the bar 1 and the projection 5, the thumb of the hand being adapted to engage the face 6 of the projection 4 upon the opposite side of the bar 1. It has been found in practice that the space between the projection 5 and the ring 3 should be of a size which will readily receive two fingers of the user's hand. The index finger of the user's hand being adapted to engage the bar 1 on the other side of the projection 5. From the above it is thought that the manner in which my invention is adapted to be used will be readily understood by those skilled in the art.

I provide slots 7 and 8 in the bar 1, said slots extending parallel to the longitudinal axis of the bar 1. Said slots 7 and 8 are 100 provided with laterally extending slots 9 and 10, said slots 9 and 10 communicating with the slots 7 and 8 respectively, and extending laterally of the longitudinal axis of the bar 1, and opening in the opposite edges 105 11 and 12 respectively of the bar 1. Each of the slots 9 and 10 has one of the walls thereof beveled as shown at 13 to facilitate the removal of the cord or twine as herein-after more fully set forth. The function of 110

BEST AVAILABLE COP

1,210,846

the above described slots 7 and 8 is to secure the free ends of a tie band, rope, or wire which may be used to bundle corn shocks, the application of this being illustrated to 5 advantage in Fig. 2, wherein the numeral 14 indicates the free ends of a cord, each of said free ends 14 having knots 15 tied therein, to prevent disengagement of the same from the slots 7 and 8 when it is desired to 10 tie the said free ends together. Another important feature of the projections 4 and 5 resides in the fact that when tying the free ends of the cord or twine together the said projections 4 and 5 provide abutments for 15 facilitating the tying of a double knot in the cord or twine, and when the same is tied, the point at which the ends are joined will come in contact with one of the abutments and a finger of the hand may be placed upon 20 the cord or twine at this point and hold the same while tying a double knot therein. When the ends of the cord or twine have been tied the same will readily spring from the slots 7 and 8 and disengage from the 25 same.

From the above description taken in connection with the accompanying drawings it will be readily appreciated by those skilled in the art that I have provided a simple, 30 cheap and durable device of the above character which can be used in a number of phases, and I desire that it be understood that I may make such changes in the details of construction thereof which shall not deviate from the spirit and scope of the appended claims.

Having thus described my invention, what

I claim and desire to secure by Letters Patent is:—

1. A device of the character described, 40 comprising a bar, lateral extensions arranged upon the opposite faces of said bar intermediate the ends thereof, a plurality of distorted recesses formed in the bar and opening on the opposite edges thereof, said 45 recesses being disposed upon either side of the lateral extensions and adapted to receive the extremities of a tying member to retain the same while tying.

2. A device of the character described, 50 comprising a bar, lateral extensions formed upon the opposite sides of said bar substantially midway the length thereof, a plurality of distorted recesses open in the opposite edges of the bar to receive a tying member, 55 said lateral extensions serving as means on which the extremities of the tying member may be placed when completing a tying operation.

3. A device of the character described, 60 comprising a bar having laterally oppositely disposed projections on the faces thereof, a plurality of substantially right angularly shaped recesses formed in the bar and opening on the opposite edges thereof and adjacent said projections to receive a tying member, said projections serving as means to hold a flexible tying element when tying.

In testimony whereof I affix my signature in presence of two witnesses.

REUBEN D. ROTH.
